IRONING MACHINE

Charles Edwin Hamilton, Sr., Hollywood, Calif.

Application June 20, 1931. Serial No. 545,637

6 Claims. (Cl. 68—9)

The invention relates to ironing tables, bucks, rolls, and the like of pressing and other ironing machines, and more particularly to the construction of spring pads utilized in connection therewith such as, for example, pads of the nature set forth in my prior U. S. Patent #1,054,407.

The present invention has for an object an improved mounting of the helical springs, employed in these pads, upon a plate or support member and whereby said springs are readily attachable to and detachable from a fastening element provided as an integral part of the plate or support, and permitting thereby defective springs to be readily removed and new ones substituted without dismantling the pad from the ironing machine and requiring, also, no particular skill nor special apparatus in the installation of the individual springs.

20 A further object of the invention resides in the provision of a novel cap member for use with the springs composing the pad.

A still further object of the invention resides in the provision of a sealing buck member for 25 use with the spring pad and wherein the degree of compression to which the springs of the pad may be subjected is limited, the arrangement being such, furthermore, as to enhance the withdrawal of moisture from the work and 30 pad.

Another object of the invention is to simplify and cheapen the construction of these spring pads.

In a prior U. S. Patent #1,445,393, granted 35 to me, there is disclosed a pad involving springs which are removably mounted in respective cups, rigidly secured to a base plate. Although these springs are removably retained in said cups, there is still involved the expense and difficulty 40 of providing and securing the cups for retaining the same.

Moreover, this expedient has not proved satisfactory in practice for the reason that it is difficult to maintain a spring within its cup 45 in perpendicular relationship to the supporting plate or the like, causing frequent interlocking of two or more adjacent springs when pressure is placed on the pad. Furthermore, it is difficult to secure an accurate and uniform diameter 50 of the many individual spring convolutions so that in many instances an uncertain fit was had of a spring in its cup, resulting in the necessity of discarding a great number of these springs in the assembly of a pad—with consequent serious loss.

In accordance with the present invention, a 55 lowermost convolution of the spring is readily applicable to and securely retained on a tubular fastener element which is integral with the base plate itself, being turned upwardly therefrom

and then inwardly to form a tubular support onto which a spring element may be snapped. This tubular element serves also to assist in the withdrawal of moisture from the pad, when means therefor are provided; and, similarly, a 65 novel type of cap element is provided for the top of a spring, the same consisting of a tubular member with flanged top overlapping the uppermost convolution, said tubular member having also a peripheral indentation or outer recess into which an upper convolution is designed to snap to hold a said cap to its spring.

The nature of the invention, however, will best be understood when described in connection with the accompanying drawing in which my 75 invention is illustrated as embodied, by way of example, in a cuff press suitable for ironing the cuffs of shirt sleeves, and in which drawing:

Fig. 1 is a part elevation and part vertical section of the upper portion of such cuff press 80 showing the padded buck and the cooperating platen thereof.

Fig. 2 is a fragmentary vertical section through the buck, pad and platen and taken on the line 2—2, Fig. 1 of the drawing.

Fig. 3 is a fragmentary plan view, on an enlarged scale, illustrating the spring pad.

Fig. 4 is a vertical section, on an enlarged scale, of a number of fastener elements for attaching the springs of the pad to their supporting plate—one spring being shown in vertical section in position and provided also with a cap; and Fig. 5 is a view in elevation with the parts shown in detached relationship.

Referring to the drawing, 10 designates a buck 95 or suitable support member for the spring pad, which is shaped to conform to the particular shape of the buck shown, although it is to be understood that the pad may be variously shaped in accordance with the desired supporting surface upon which it is utilized. In pressing machines such as are utilized for the ironing of cuffs of shirts and embodying the angular shaped support or buck, as indicated in Fig. 1 of the drawing, it is particularly difficult to suitably 100 retain the springs of the pad in proper position and to prevent their interlocking. As shown, the individual springs 11 are of the helical type and are designed to be retained upon a suitable support as the base plate 12, which, in turn, is to be secured in the present embodiment to the upper surface 13 of the buck. The buck, furthermore, may be provided with a suction chamber 14 communicating with a series of openings 15 through 110 the upper surface for the purpose hereinafter set forth; and suitable suction connections are made to the chamber 14 through a hose or the like 16 having the branches 17 and 18. A steam-heated platen 20 cooperates with the top of the 115

pad in the usual manner in the pressing of cuffs therebetween.

The individual springs 11 with holding plate 12 are, furthermore, arranged to be contained 5 within a casing formed by the front and rear walls 25 and 26, respectively, extending upwardly from the buck and by side walls 27 and 28, the tops of the springs, however, protruding normally somewhat beyond the upper edges of these 10 walls. Thus when the buck 10 is raised in the usual manner, the upper edges of the casing walls serve as stops for the upward movement of the buck and serve to limit the degree of compression of the spring elements of the pad there- 15 by preventing crushing and the application of undue force thereon. Any abnormal thickness as would be produced by a button and the like would, nevertheless, be accommodated, if located within the casing space, by further compression 20 of the springs engaged. In view of the thicker or bunched portion of the inner part of the cuff it is desirable, also, to make the height of the front wall 25 slightly less than that of the rear wall 26 in order to accommodate the 25 different thicknesses. Furthermore, when the platen contacts through the goods with the upper edges of the said casing walls, it substantially seals the casing thereat and renders more 30 effective the withdrawal of moisture from the pad and goods being ironed.

As the wear on the springs and pressing devices of the aforesaid type is particularly heavy, necessitating frequent replacement and as the springs in view of the inclined location thereof 35 must be securely retained and properly positioned on their supporting plate, provision is made to mount the same in a novel manner thereon and at the same time afford means for enhancing the withdrawal of the moisture from 40 the goods.

Reference being had particularly to Figs. 3-5 of the drawing, the plate 12 is shown as having been pierced to provide an axial opening 30 and is formed to afford an upturned wall 31 with 45 outer recess or peripheral groove 32 and an in-turned end 33. Over this upwardly extending stud or fastener element thus provided, the lower end of a spring is slipped to cause a lowermost convolution, as the convolution 34, to snap into the recess 32 and thus securely retain 50 the spring to the plate.

A similar metal element may be provided as a cap for the top of the spring, if desired. As indicated in Fig. 4, this cap is constituted by 55 a cylindrical tubular portion 35 having the outer recess or groove 36 at its upper end and the flange 37. An inturned portion 38 extends upwardly and is pierced as at 39 so that when the top of the pad is in contact with the goods 60 withdrawal of moisture will not be impeded in passing through the individual springs. Openings 39' may, also, be provided in the annular gutter thus formed to drain the same of any water of condensation.

65 A suitable cover cloth 40 is to be provided in the usual manner over the tops of the springs or, rather, the flanges 37 of the caps.

By the novel fastener arrangement hereinbefore described, a spring as a whole may not 70 only be readily attached to and suitably positioned on its supporting plate, but is quickly and conveniently withdrawable therefrom for

replacement, when required. Moreover, by constituting the said fastener elements, and the caps as well, as tubular members, the withdrawal of moisture from the goods and pad is facilitated and better ironing results.

80

I claim:

1. In an ironing pad of the character set forth: a base plate having tubular integral fastener elements turned upwardly therefrom and flaring outwardly to removably receive and snap 85 thereon lower terminal convolutions of helical springs adjacently disposed over the surface of said plate, and a tubular downwardly flaring cap element affording an outer recess into which the upper terminal convolutions of a spring are 90 adapted to snap.

2. In an ironing pad of the character set forth: a base plate having integral fastener elements turned upwardly therefrom to removably receive and retain helical springs adjacently 95 disposed over the surface of said plate, lower terminal convolutions of a spring being adapted to snap onto a fastener element, and a tubular cap element flanged at the top and flaring downwardly therefrom to afford an intermediate outer recess into which the upper terminal convolutions of a spring are adapted to snap.

3. An ironing buck comprising a rigid casing closed at the sides and ends, a plurality of helical adjacent springs, tubular members to support the springs on the casing bottom to afford an ironing pad, and a platen movably mounted with reference to the said casing to compress the springs of said pad, the degree of compression being limited by contact between the platen 105 and the upper edges of the walls of the casing, said platen thereby also sealing the casing except for the openings through the fastener elements.

4. An ironing buck, comprising a casing closed 115 at the sides and ends and the front side being lower than the rear side, a plurality of helical adjacent springs supported on the casing bottom to afford an ironing pad, and a platen movably mounted with reference to the said 120 casing to compress the springs of said pad, the degree of compression being limited by contact between the platen and the upper edges of the walls of the casing, and the platen thereby also sealing the said casing.

5. An ironing pad of the character set forth, comprising a base plate carrying tubular fastener elements, turned upwardly therefrom to provide an enlarged head portion with neck portion intermediate the head and plate, and removable helical springs adjacently disposed 130 over the surface of the plate and having a lower terminal convolution fitting over the head portion of the fastener element for snap engagement with the said neck portion thereof.

125

6. An ironing pad of the character set forth, comprising a base plate carrying tubular fastener elements, turned upwardly therefrom to provide an outwardly flaring or head portion with neck portion intermediate the head and plate, and removable helical springs adjacently disposed 140 over the surface of the plate and having a lower terminal convolution fitting over the head portion of the fastener element for snap engagement with the said neck portion 145 thereof.
